POTENTIOMETER

Robert L. Reid, Indianapolis, Ind.

Application November 29, 1952, Serial No. 323,327

13 Claims. (Cl. 201—52)

The present invention relates to a variable resistor or potentiometer primarily intended for use in electronic circuits particularly in connection with radio and television apparatus.

The variable resistor, or variable potentiometer, as it is called, has been used almost exclusively for controlling the performance of various electronic circuits. In the case of the radio, it has been used to vary the power output of the receiver—thus, the volume control. In the field of television, aside from the necessity for varying the audio output, there are many circuits whose performance must be nicely regulated in order to obtain a more perfect picture. Some of these circuits control the brightness, others the vertical and horizontal position of the picture on the screen, and others bring the picture into proper focus, and there are many others performing varied and sundry functions all essential to proper television reception.

Because of the ever increasing numbers of such controls required in the television field, that part of the bill of material represented by such controls has come to represent a much larger proportion of the cost of a television apparatus than it did in the case of a radio receiver.

It is, therefore, the primary object of my invention to provide a device of this character extremely simple in design, relatively inexpensive to manufacture, and yet highly efficient and trouble free in its operation.

Further objects will become apparent as the description proceeds.

To the accomplishment of the above and related objects, my invention may be embodied in the forms illustrated in the accompanying drawings, attention being called to the fact, however, that the drawings are illustrative only, and that change may be made in the specific constructions illustrated and described, so long as the scope of the appended claims is not violated.

Fig. 1 is an elevational view of an embodiment of my invention;

Fig. 2 is a longitudinal sectional view through the device of Fig. 1;

Fig. 3 is a transverse sectional view through said device taken substantially on line 3—3 of Fig. 2;

Fig. 4 is a transverse sectional view similar to Fig. 3 but taken substantially on line 4—4 of Fig. 2;

Fig. 5 is a transverse sectional view similar to Fig. 3 but taken substantially on the line 5—5 of Fig. 2; and

Fig. 6 is a longitudinal sectional view similar to that of Fig. 2 but showing a modified form of my invention.

Referring more particularly to the drawings, it will be seen that I have shown a body element 10, of dielectric material, having an axial bore 11 therethrough and a chordal slot 12 opening through the periphery near the midpoint thereof. An elongated resistor element 13 is received in bore 11 for axial reciprocation therein. In the embodiment illustrated in Figs. 1—5, such element comprises a dielectric core 14 surrounded by a sleeve 15

of electrical resistance material such as carbon or the like, such sleeve being intimately fixed to core 14.

A split ring 16 of resilient, electrically conducting material is sleeved on body 10 and has a portion 17 thereof turned out of the circle of the ring to lie in a chord thereof. Such portion is entered through the chordal slot 12 in body 10 and resiliently engages the periphery of the element 13 to establish electrical contact between ring 16 and the resistor element 13. The ring is preferably formed with a solder lug or eye 18 to serve as an electrical terminal.

Near one end of body 10 a U-shaped element 19, comprising a pair of substantially parallel pin portions 20 and 21, transaxially penetrates the walls of body 10 and acts as an abutment member to effectively block one end of the body bore 11. One of the pin portions is preferably formed with a solder lug or eye 22 to serve as an electrical terminal. A coiled spring 23 is confined in bore 11 between element 19 and the adjacent end of resistor element 13.

Near the other end of body 10 a second U-shaped element 24, similar to element 19 and comprising a pair of substantially parallel pin portions 25 and 26, transaxially penetrates the walls of body 10 and acts as an abutment member to effectively block the other end of the body bore 11. One of the pin portions is preferably formed with a solder lug or eye 27 to serve as an electrical terminal. A second coiled spring 28 is confined in bore 11 between element 24 and the adjacent end of resistor element 13.

Spring 23 and 28 serve as yieldable conductor means for establishing electrical paths from terminal 18 through resistor element 13, and thence through the respective springs to the respective terminals 22 and 27. By shifting resistor element 13 axially relative to ring portion 17, the lengths of resistor element 13 included in said respective paths between portion 17 and the abutment elements 19 and 24 are oppositely varied. An electrical potential applied to terminal 18 can thereby be divided between the terminals 22 and 27, the value to each depending on the setting of the element 13.

Some means must be provided for axially adjusting resistor element 13 and, in the embodiment illustrated in Figs. 1—5, such means comprises a screw 29 fixed to (or journaled in) the dielectric core 14 of element 13 and projecting therefrom substantially coaxially with respect to bore 11. A mounting plate 30 is suitably fixed to one end of body 10 and has a threaded aperture 31 therein substantially coaxial with screw 29. Said screw is threadedly received through aperture 31 and extends beyond plate 30, where it may be manipulated to shift resistor element 13 axially in the body bore. A nice adjustment of the resistor element can thereby be had relative to the abutment members 19 and 24.

In Fig. 6, I have shown another means for adjusting the resistor element axially in bore 11. Therein, the resistor element 32 is peripherally threaded as at 33. The ring portion 17 enters through slot 12 and interengages with thread 33. Element 32 is slotted as at 34 or otherwise formed for the operative engagement thereof by a tool enterable through a port 35 in the mounting plate 36. By rotating the resistor element in the body, the coaction between the thread 33 and the ring portion 17 will shift the element toward member 19 or member 28, depending on the direction of rotation of element 32.

By the use of my device, the now considerable portion of the cost of electronic apparatus, especially in the field of television, is substantially reduced. At the same time, the quality of performance of the various circuits is in no way lessened, but, on the other hand, is, in many instances, greatly improved by the use of this invention.

I claim as my invention:

1. A potentiometer comprising a dielectric frame, a first terminal stationarily fixed in said frame, an elongated resistor element axially reciprocable in said frame, a second terminal stationarily fixed in said frame and peripherally, slidably engaging said resistor element, electrical-conductor means yieldably connecting said first terminal with one end of said resistor element, and adjustment means for shifting said resistor element axially, relative to said second terminal, through a stroke substantially equal to the length of said resistor element while said second terminal maintains sliding engagement with said resistor element.

2. A potentiometer comprising a dielectric frame, a first terminal stationarily fixed in said frame, an elongated resistor element axially reciprocable in said frame, a second terminal stationarily fixed in said frame and peripherally, slidably engaging said resistor element, electrical-conductor means yieldably connecting said first terminal with one end of said resistor element, adjustable means for shifting said resistor element axially relative to said second terminal while remaining in sliding engagement therewith, a third terminal fixed to said frame, and electrical-conductor means yieldably connecting said third terminal and the other end of said resistor element.

3. The device of claim 2 in which the first said conductor means comprises a coiled spring confined between said first terminal and said one end of said resistor element, and the second conductor means comprises a second coiled spring confined between said third terminal and said other end of said resistor element.

4. A potentiometer comprising a dielectric body, a first terminal stationarily fixed in said body, an elongated resistor element axially reciprocable in said body, a second terminal stationarily fixed in said body remote from said first terminal and slidably engaging the periphery of said resistor element, a coiled, electrically-conductive spring confined between said first terminal and the adjacent end of said resistor element, and means for axially adjusting said resistor element relative to said first terminal while maintaining said second terminal in peripheral engagement with said resistor element.

5. The device of claim 4 in which said resistor element is peripherally threaded and said second terminal operatively engages said thread whereby rotation of said resistor element axially shifts said resistor element, such structure comprising the said means for axially adjusting said resistor element.

6. The device of claim 4 including a third terminal stationarily fixed in said body remote from said second terminal and on the side thereof opposite said first terminal, and a coiled spring confined between said third terminal and the adjacent end of said resistor element.

7. A potentiometer comprising a body of dielectric material having an axial bore therethrough and a radially-opening aperture near the midpoint thereof, an abutment member of conducting material stationarily fixed near one end of said body transaxially to the bore therein, an elongated resistor element axially reciprocable in said body bore, a contact carried by said body and enterable through the radial aperture therein to resiliently and slidably engage the periphery of said resistor element, a coiled spring confined in said body bore between said abutment member and the adjacent end of said resistor element, and means for axially adjusting said resistor element relative to said abutment member.

8. The device of claim 7 in which the last said means comprises a plate stationarily fixed on said body to close one end of said bore and having a threaded aperture therein substantially coaxial with said bore, and a screw

operatively connected to said resistor element and threadedly received through the aperture in said plate.

9. The device of claim 7 in which said resistor element is formed with a peripheral thread and said contact is resiliently held in operative engagement with such thread, such structure comprising the said means for axially adjusting said resistor element.

10. The device of claim 7 comprising a second abutment member of conducting material stationarily fixed near the other end of said body transaxial to the bore therein, and a second coiled spring confined in said body bore between said second abutment member and the adjacent end of said resistor element.

11. The device of claim 10 in which each of said abutment means comprises a pin passing transaxially through said body and projecting beyond said body to form an electrical terminal and said contact comprises a split ring having a portion thereof turned to follow a chord of the ring, said portion, when said ring encircles said body, passing through the radial aperture formed therein to resiliently engage the periphery of said resistor element.

12. A potentiometer comprising a body of dielectric material having an axial bore therethrough and a chordal slot opening through the periphery near the midpoint thereof, a split ring of electrically-conductive material surrounding said body and having a portion turned to follow a chord thereof, such portion passing through the chordal slot in said body, an elongated resistor element axially reciprocable in the bore in said body and peripherally engaged by said ring portion, an electrically-conductive first pin transaxially penetrating said body near one end thereof, an electrically-conductive second pin transaxially penetrating said body near the other end thereof, a first coiled spring confined in said body bore between said first pin and the adjacent end of said resistor element, a second coiled spring confined in said body bore between said second pin and the adjacent end of said resistor element, a cap closing one end of said body and having a threaded aperture therein substantially coaxial with said body bore, and a screw operatively connected to said resistor element and threadedly received through the aperture in said cap.

13. A potentiometer comprising a body of dielectric material having an axial bore therethrough and a chordal slot opening through the periphery near the midpoint thereof, a split ring of electrically-conductive material surrounding said body and having a portion turned to follow a chord thereof, such portion passing through said chordal slot in said body, an elongated resistor element axially reciprocable in the bore in said body and formed with a peripheral thread therein, said ring portion being resiliently urged into threaded cooperation with said resistor element thread, a first electrically-conductive pin transaxially penetrating said body near one end thereof, a second electrically-conductive pin transaxially penetrating said body near the other end thereof, a first coiled spring confined in said body bore between said first pin and the adjacent end of said resistor element, a second coiled spring confined in said body bore between said second pin and the adjacent end of said resistor element, and means for rotating said resistor element relative to the chordal portion of said ring to shift said resistor element axially in said body bore.
